LOOSE LEAF BINDER

Filed Aug. 12, 1929

INVENTOR:
BY William B. Osman,
E. J. Silvius,
ATTORNEY.

UNITED STATES PATENT OFFICE

WILLIAM B. OSMAN, OF INDIANAPOLIS, INDIANA

LOOSE LEAF BINDER

Application filed August 12, 1929. Serial No. 385,387.

This invention relates to the class of apparatus which is designed to be used for binding leaves of books together or for binding sheets of paper or other material, such as catalogues, price lists, photographic illustrations of factory products, wall paper samples, or other articles, the invention having reference more particularly to a loose leaf binder of the above-mentioned character having means for sealing it so as to prevent changes of records without detection.

An object of the invention is to provide an improved loose leaf binder that shall be of such construction as to be adapted to removably bind together a large number of book leaves or sheets into the form of a book and permit the insertion of additional leaves or sheets.

Another object is to provide an improved loose leaf binder which shall be of simple construction and adapted to be readily operated, and to be easily handled or cared for.

A further object is to provide an improved metallic loose leaf binder that shall be of such construction as to be adapted to have covers readily secured thereto, as dust guards or for other useful or ornamental purposes, and which shall be strong, durable and economical in use.

With the above-mentioned and other objects in view, the invention consists in an improved loose leaf binder having novel features of construction enabling the binder to be self-contained or unitary, and adapted to be readily attached to a cover, the invention including sealing means to insure permanency of bound records or other recorded matters of importance that may be required to be preserved without alterations; and further, the invention consists in the novel parts and in the combinations and arrangements of parts as hereinafter particularly described and further defined in the appended claims.

Referring to the accompanying drawings,—Figure 1 is a perspective view of a loose leaf binder constructed substantially in accordance with the invention minus the sealing means which if present would obscure other important devices, portions of

the cover of the binder being broken away; Fig. 2 is a fragmentary perspective view of the binder showing a metallic cover applied thereto; Fig. 3 is a fragmentary perspective view of the binder structure having the improved sealing device applied thereto; Fig. 4 is an end view of the binder on an enlarged scale clearly showing devices whereby to tightly secure the leaves or sheets together in the binder; Fig. 5 is a fragmentary vertical section showing details of features of the binder and the cover structure; Fig. 6 is an enlarged horizontal section of slot-closing means and securing means of the structure adapted to be sealed looking upward as on Fig. 4; Fig. 7 is a detail of a binding or clamp screw adapted to prevent its being carelessly withdrawn and misplaced; Figs. 8 and 9 are perspective views of parts of novel sealing devices comprised in the invention; and Fig. 10 is a sectional detail of the improved sealing device applied to the clamping devices of the binder.

Similar reference characters in the various figures of the drawings indicate corresponding elements or features of construction herein referred to in detail.

A practical embodiment of the invention comprises oppositely arranged frame parts 80 having plates 1 and 2 between which loose leaves or sheets are to be placed, the plate 1 having hollow posts 3 and 4 fixed thereon that telescopically receive smaller posts 5 and 6 secured to the opposite plate 2. Preferably the plate 1 is provided with thin posts 7 intermediately of the other posts, and the plate 2 is provided with a suitable number of hollow posts 8 telescopically co-operating with the posts 7. The plate 1 has relatively angular tie plates 9 and 10 on its opposite ends, the plate 2 having tie plates 11 and 12 on its opposite ends to adjustably co-operate with the plates 9 and 10 respectively to constitute longitudinally adjustable ties or end members of 95 the binder frame. Each of the plates 9 and 10 is provided with a binding screw 13 threaded into a suitable hole adjacent to its end, the screw having a broad head 14 thereon; and to prevent loss of the screws each one 100

has a retaining screw 15 threaded therein and having a head 16 to engage the opposite side of the plate. As preferably constructed the screw 13 has a right-hand thread and the screw 15 has a left-hand thread to prevent separation of the screws when loose. The plates 11 and 12 have longitudinal slots 17 and 18 receiving the two clamp screws respectively and permitting the plates 11 and 12 to be drawn away from the plates 9 and 10 respectively. To prevent unintentional separation of the two parts of the frame the end of each slot 17 and 18 is closed by a suitable cross-bar or barrier 19 which may be permanently fixed in place but preferably has one end connected to the slotted tie plate by means of a pivot pin 20 and its opposite end latched to a stud 21 fixed to the plate on the opposite side of the slot, the bar 19 being composed of spring-metal so that it can be sprung into or out of contact with the stud, the end of the bar being notched to receive a portion of the stud.

For the purpose of preventing access to the binding screws 13 if they are tightened following the filling of the binder with leaves or sheets, each screw head is covered and sealed by means of a cap 22 having opposite base plates 23 and 24 integral therewith that are placed against the outer side of the slotted tie plate and provided with upstanding slightly inclined spring-latches 25 on their inner edges whereby to secure the cap in place so as to effectively cover the screw head. A pair of cooperating clamps for each cap is provided and comprises each a web plate 26 adapted to span the edges of the two tie sections and one of the base plates of the cap, and it has a relatively angular lip 27 adapted to engage the inner side of the inner one of the tie plate sections, the web having on its opposite edge a pair of fingers 28 spaced apart so as to span the edge of the cap and have connection with the fingers of the opposite clamp of the bar, as by tongue and groove connections 29 so as to form match-joints, each finger having an under-cut notch 30 in its under side to receive one of the spring catches 25 under compression whereby to securely hold the plates 23 and 24 and the cap in place and prevent removal without destructive violence and leaving evidence of tampering. Thus the sealing of the binder is permanent.

The binder being self-contained may be used without a cover but preferably is provided with a separately made cover which for the purpose of minimizing fire hazards may be entirely or partially metallic. When composed of book cover material the cover comprises a stiff side base strip 31 having a relatively angular back portion 32, the strip being rigidly secured to the frame plate 1 by means of screws 33, each screw preferably having a nut 34 thereon that is embedded in the strip 31 and the frame plate, the portion

32 extending back of the tie plates. Likewise a strip 31' is similarly secured to the frame plate 2 and has a back portion 32' extending in sliding connection with the back portion 32. The cover includes stiff side boards 35 and 35' having each a flexible hinge-like connection 36 with the base strip 31.

In the event that metallic side boards 35 are preferred, a base strip or hinge plate 38 is provided and secured against the outer side of the frame plate 1 by means of the screws 33 and if desired is inserted between the frame plate and the strip 31 of the back portion. The plate 37 has hinge members 39 thereon matching hinge members 40 on the plate 38 and connected thereto by a hinge pin 41.

In practical use the loose leaves or sheets if they are perforated and also slitted in their back edge may be slipped onto the binder posts. The cross-bars 19 are to be unlatched and swung to permit the screw 13 when slightly slackened to pass out of the slots 17 as the frame parts are drawn apart to separate the sections of the posts so that the post sections may be entered into perforations with which the loose leaves or sheets are usually provided. The frame parts are to be connected together as before and the leaves are to be bound together and to the frame plates 1 and 2 under more or less pressure as may be desired, after which the screws 13 are again tightened. When the binder is filled as may be desired the binding screws may be covered and sealed as above described so as to prevent either extraction or insertion of leaves in the binder. The binder may be handled as in common practice to refer to or inspect the leaves or sheets bound therein.

What is claimed is:

1. A loose leaf binder having two relatively adjustable frame parts with posts thereon to hold leaves together, securing devices to rigidly fasten the frame parts together, two cover parts independently secured rigidly to the frame parts and having cooperating back portions, and sealing devices to conceal the securing devices attachable securely together and to the frame parts.

2. In a loose leaf binder, the combination of a pair of frame parts having ties connected thereto, each tie comprising a plain plate and a co-operating slotted plate, a binding screw threaded in the plain plate and extending through and engageable with the slotted plate, and a cross-bar pivoted on the slotted plate on one side of the slot and latched to the plate on the opposite side of the slot.

3. In a loose leaf binder, the combination of a pair of frame parts having ties connected thereto, each tie comprising a plain plate and a slotted co-operating plate, a binding screw threaded into the plain plate and operating in the slotted plate, co-operating posts on the

frame parts, and a plurality of sealing devices for the binding screws comprising each a cap to cover the screw head provided with base plates having spring-catches, and a pair of clamps having co-operating fingers having notches to hold the spring-catches.

4. In a loose leaf binder, a binder frame comprising a pair of opposite frame plates, and a pair of extensible ties comprising each 10 a plain tie-plate fixed to one of the frame plates and a slotted tie-plate fixed to the remaining frame plate, co-operating post section secured to the frame plates respectively, binding screws threaded in the plain tie-plates 15 respectively and operating in the adjacent slotted tie-plates respectively, each screw having a head thereon engaging the outer side of the slotted tie-plate, and two reversely-pitched screws threaded into the inner ends of 20 the binding screws respectively and having each a head to engage the inner side of the adjacent plain tie-plate.

In testimony whereof, I affix my signature on the 9th day of August, 1929.

WILLIAM B. OSMAN.
